UNITED STATES PATENT OFFICE

WALTER J. CORMAY, OF AUBURNDALE, MASSACHUSETTS

FIXTURE SUPPORT AND METHOD OF MAKING THE SAME

Application filed June 8, 1927. Serial No. 197,500.

This invention relates to improvements in supports for electric fixtures and the like and the object thereof is to provide a fixture support which can be readily and adjustably clamped upon an anchoring device, such as a supporting bar adapted to be secured to the wall or ceiling.

A further object of the invention is to provide an electric fixture support comprising a section of a threaded pipe, which for convenience in description is referred to herein as a nipple, and which is so constructed as to present a transverse aperture to receive the supporting bar, with a nut 10 upon the nipple operable to clamp the bar against a wall of the aperture through which the bar extends.

A further object of the invention is to provide a nipple of this character which can 20 be economically constructed.

A further object of the invention is to provide a fixture-supporting device of the character above described which can be readily associated with an outlet box and in which 25 construction the outlet box may be mounted upon the supporting bar and the nipple adjusted lengthwise of the bar within said outlet box.

A further object of the invention is to provide 30 a novel blank for producing a fixture support of the character disclosed herein.

Other objects and features of the invention will more fully appear from the following description and the accompanying drawings and will be particularly pointed out in 35 the claims.

In the drawings:

Fig. 1 is a vertical sectional view of an outlet box mounted upon a supporting bar 40 and having a fixture-supporting nipple embodying the present invention adjustably mounted upon the bar;

Fig. 2 is a transverse sectional view through the wall of the nipple in the plane 45 of the aperture which receives the supporting bar, illustrating also the supporting bar extending through said aperture;

Fig. 3 is a plan view of a threaded metal plate adapted to be formed into a pipe section or nipple, said plate having extensions

from one longitudinal edge, adapted to be bent to provide a bar-supporting aperture;

Fig. 4 is an elevation of a nipple formed from the plate illustrated in Fig. 3 with the extensions bent to receive the supporting bar 55 which is illustrated in cross section;

Fig. 5 is a view, mainly in elevation, of the construction shown in Fig. 4, viewed at right angles to the position illustrated in Fig. 4; and,

Fig. 6 is a modified construction of the device shown in Figs. 4 and 5.

The present application is a continuation in part of my prior application Serial Number 120,011 (Patent No. 1,647,505) filed July 2, 1926, for improvements in outlet boxes and fixture supports.

The installation of usual types of outlet boxes and fixture supports presents many problems owing to different structural conditions of buildings in which they are installed.

Chambered outlet boxes are usually required to be embedded in the walls in such a manner that the face of the box is flush with the surface of the wall. As outlet boxes 70 are ordinarily installed by screwing the base to a suitable support, various expedients have to be employed to obtain proper installation upon different types of structure, such as, usual lath and plastered walls, constructions in which the lath and plaster are supported upon furring, constructions in which metal lathing is employed, and particularly drop ceiling constructions in which metal lathing is carried by channel bars which are supported from hangers depending from the floor above. Difficulty is frequently experienced in obtaining proper alinement of fixtures which depend from the outlet boxes in view of the impossibility to obtain proper 75 alinement of the boxes themselves. The prior application above identified relates to the production of an outlet box construction in which the outlet box is adapted to be adjustably mounted upon a supporting bar 80 having holes located at suitable distances from each end to receive nails or screws by means of which it may be secured to the furring, girders, or studding, or other portions of the building structure.

100

The present invention relates particularly to the fixture support which is so constructed as to be adjustable upon the supporting bar which, in the construction illustrated, extends through the outlet box. The present invention, however, contemplates a construction in which a fixture support in the form of a nipple may be readily clamped upon a supporting bar, or upon any suitable anchoring device independently of the outlet box. In its broader sense the invention contemplates the production as an article of manufacture of a nipple having means to receive a bar or anchoring device with means for clamping the nipple upon the anchoring device.

The construction illustrated in Fig. 1 of the drawing comprises a chambered outlet box having a base 1 provided with suitable knock-outs 2 and having a peripheral wall 3, likewise provided with knock-outs 4 through which the ends of cables 5 and 6 may be introduced into the box, the cables 5 and 6 being shown in Fig. 1 as entering the box and clamped therein by a yoke 7 engaging said cables, with a screw 8 passing through the yoke 7 and seated in the base of the box acting to clamp the cables against the bottom of the box. The outlet box illustrated in Fig. 1 is provided with oppositely disposed apertures 9 and 10 through which a supporting bar 11 extends, the supporting bar being shown as secured to suitable furring 12 forming part of the building structure. The peripheral wall of the outlet box is provided with diametrically opposite, inwardly extending, ears 13 having screw threaded apertures in which screws 14 are seated, the screws 14 bearing at their ends against the supporting bar 11 and clamping the same against the opposite walls of the apertures 9 and 10. A canopy 15 serves to close the open face of the outlet box, this canopy being provided with inwardly extending ears 16 having bayonet slots to receive the heads of the screws and by slight rotation to bring the shank of the screws into the narrow portions of the bayonet slot thereby detachably securing the canopy to the outlet box.

The present invention relates particularly to the electric fixture support within the box which is adjustably mounted upon the supporting bar 11. In the construction disclosed in Fig. 1, the fixture-supporting device is in the form of a short pipe section or nipple 17 the cylindrical body of which is screw threaded. Diametrically oppositely disposed apertures 18 and 19 (see Fig. 2) are formed in the wall of the nipple by milling, or otherwise, and desirably are of rectangular form and of such size as to permit the supporting bar 11 to be inserted therethrough. By reason of this construction the electric fixture support or nipple may be readily adjusted lengthwise of the bar. A nut 20, upon the

nipple, may be screwed up to engage one face of the supporting bar and clamp the bar against the opposite walls of the apertures 18 and 19. By reason of this construction the fixture support or nipple may be readily brought into alinement with other fixture supports although the outlet boxes themselves may be out of alinement in the building construction. By reason of the present invention, therefore, an adjustable fixture support is provided which can be readily assembled and adjusted thereby enabling the outlet box to be installed with less care than would be otherwise necessary to provide the proper alinement of the fixtures.

Obviously the nipple may itself be secured adjustably upon a supporting bar or other anchoring device independently of the outlet box and the nipple, therefore, is adapted to provide convenient means for supporting electric fixtures and other devices from the ceiling or wall of the building as the supporting bar can be readily attached to the furring, beams, or studding of the building, and the nipple adjustably secured upon the supporting bar. The articles to be supported may thereupon be attached to the projecting screw threaded end of the nipple.

Inasmuch as the milling of nipples to provide oppositely disposed apertures to receive the supporting bar is somewhat difficult and costly, a further object of the invention is to provide a nipple which can be readily constructed at comparatively little expense. This is accomplished by providing a threaded blank preferably having extensions from one edge thereof which will extend from diametrically opposite portions of the nipple when rolled into cylindrical form, the ends of such extensions being bent toward each other to provide a guideway presenting alined bar-receiving apertures diametrically of the nipple. In constructing such a nipple a flat plate 21 of sheet metal is provided of substantially rectangular form with extensions 22 and 23 extending from one edge thereof, each being located at equal distances from the adjacent end of the blank and the longitudinal middle of the blank and of a length substantially equal to the radius of the nipple so that when the blank is rolled into cylindrical form the extensions 22 and 23 will extend from diametrically opposite portions of the nipple.

The nipple may be screw threaded in any desired manner. For the purpose of economy, screw threads 24 are formed in the plate 21, portions 25 of said threads desirably being also formed upon the extensions 22 and 23. After the plate 21 has been bent or rolled into cylindrical form, for example as shown in Figs. 4 and 5, the end portions 26 and 27 of the extensions 22 and 23 are bent toward each other at a distance from the edge 28 of the nipple. Obviously the threaded plate 21 may be bent or rolled to provide either an

externally or an internally threaded nipple adapted to receive a nut or other fitting having complementary screw threads to engage the thread of the nipple and adapted to be 5 screwed up sufficiently to engage the bar 11 and clamp it against the bent sections 26 and 27 of the extensions 22 and 23. The bent portions of these extensions desirably are of such length that the ends thereof abut, as 10 illustrated in Fig. 4, and may, if desired, be connected together by welding. The extensions thus bent provide a loop which presents a rectangular aperture 29 to receive the bar 11. A nut 30 upon the cylindrical screw 15 threaded portion of the nipple is employed to clamp the bar against the bent sections 26 and 27 of the extensions which form the wall of the aperture through which the bar 11 extends. By threading a portion or all of the 20 extensions 22 and 23 the nut can be screwed up far enough to insure the proper clamping of the bar even though the bar be of less thickness than the width of the aperture through which it extends. Thus the nipple is adapted 25 to receive bars of different thickness.

In Fig. 6 a modified construction is shown in which the legs of a U-shaped bar or plate 31 extend into one end of the nipple 32 and are secured thereto by spots or lines of brazing or soldering 33. In this construction the bar 11 extends through the aperture provided by the U-shaped member 31 and the bar is clamped against the U-shaped member by a nut 34. Obviously various other forms of the 30 invention may be produced within the meaning and scope of the following claims. It will, therefore, be understood that the particular embodiments of the invention shown herein are illustrative in character and not 35 restrictive of the claims.

Having thus described the invention, what is claimed as new, and desired to be secured by Letters Patent, is:

1. An adjustable support for electric fixtures and the like comprising a nipple having 45 at one end diametrically opposite relatively narrow extensions of bendable material, the end portions of which are bent toward each other at a distance from the circular end of 50 the nipple to provide a transverse aperture to receive a supporting bar and a nut on said nipple operable to clamp the bar against the bent portions of said extension.

2. An adjustable support for electric fixtures and the like comprising a threaded 55 plate of cylindrical form presenting a nipple having at one end diametrically opposite relatively narrow extensions of bendable material, the end portions of which are bent toward each other into the same plane at a distance from the circular end of the pipe to provide a rectangular transverse aperture to receive a supporting bar, screw threads upon 60 said nipple and a nut thereupon operable to 65 clamp the bar against said extension.

3. An adjustable support for electric fixtures and the like, comprising a nipple of substantially uniform diameter throughout, having at one end a relatively narrow extension of bendable material of substantially uniform thickness and width, a portion of which extends transversely of said nipple, thereby to provide means to engage a supporting bar, and a nut on said nipple operable to clamp the bar against said transverse portion of the 70 extension. 75

4. A blank for making supporting nipples for electric fixtures which comprises a rectangular plate of a length corresponding to the circumference of the cylindrical nipple to be formed and having longitudinally extending screw-thread grooves and means to provide a transverse aperture through said 80 nipple when formed. 85

5. A blank for making supporting nipples for electric fixtures which comprises a rectangular plate of a length corresponding to the circumference of the cylindrical nipple to be formed and having longitudinally extending screw-thread grooves and an extension 90 projecting from one edge adapted to be bent into parallelism with the plane of said edge. 95

6. A blank for making supporting nipples for electric fixtures which comprises a rectangular plate of a length corresponding to the circumference of the cylindrical nipple to be formed and having longitudinally extending screw-thread grooves and narrow extensions projecting from one edge thereof, 100 each of which extensions is located at substantially equal distances from the adjacent end and from the middle of the length of said plate and of a length substantially equal to the radius of the nipple. 105

In testimony whereof, I have signed my name to this specification.

WALTER J. CORMAY.
